UNITED STATES PATENT OFFICE.

LUCIEN BIVA, OF BROOKLYN, NEW YORK, ASSIGNOR TO PENNSYLVANIA TEXTILE MILLS, INC., OF CLIFTON, NEW JERSEY, A CORPORATION OF NEW JERSEY.

DESIGN FOR A TEXTILE FABRIC.

Application filed February 9, 1928. Serial No. 25,327. Term of patent 3½ years.

To all whom it may concern:

Be it known that I, LUCIEN BIVA, a citizen of France, residing in Brooklyn, county of Kings, State of New York, whose post-office address is No. 295 Fifth Avenue city, county, and State of New York, have invented a new, original, and ornamental Design for a Textile Fabric, of which the following is a specification, reference being had to the accompanying drawings, forming part thereof.

The figure is a plan view of a textile fabric showing my new design.

I claim:

The ornamental design for a textile fabric substantially as shown.

LUCIEN BIVA.
